HYDRAULIC UNDERREAMER

Reuben C. Baker, Coalinga, Calif., assignor to
Baker Oil Tools, Inc., Vernon, Calif., a corpora-
tion of California

Application November 26, 1946, Serial No. 712,383

3 Claims. (Cl. 255—76)

1

The present invention relates to underreamers for enlarging the size of well bores, and more particularly to underreamers whose cutters are expanded to operative positions by hydraulic pressure.

Heretofore, plungers or piston devices for expanding underreamer cutters outwardly have been restricted at their lower portions for the purpose of building up sufficient back pressure on the high pressure side of the piston plunger to force the cutters outwardly against the wall of the well bore. The fluid expands through such restrictions and exhausts onto the cutters, to cleanse them of the formation material and remove such material in the drilling mud to the top of the well bore.

It has been found that the expansion of the fluid through the restrictions or nozzles erodes the main body of the underreamer and lessens its life considerably, at a substantial economic loss. Not only is the body eroded, but the plunger device itself is fluid cut extensively.

Accordingly, it is an object of the present invention to provide a hydraulic plunger or piston in an underreamer which exhausts fluid onto the cutters in such manner as to avoid cutting or eroding of the cutter body.

Another object of the invention is to provide an underreamer embodying a plunger or piston for expanding the underreamer cutters, in which the wear in the plunger or piston itself is largely minimized.

One form which the invention may assume is exemplified in the following description and illustrated by way of example in the accompanying drawings, in which:

Fig. 1 is a side elevation, partly in section, of a rotary underreamer.

Fig. 2 is a longitudinal section taken along the line 2—2 on Fig. 1.

Fig. 3 is a cross-section taken along the line 3—3 on Fig. 1.

Underreamers of the type disclosed in the drawings are described in detail in United States Patent No. 1,857,616. They include an elongate main supporting body 10 provided with an upper threaded box 11 attachable to the lower end of a string of drill pipe 12 or the like, by means of which the underreamer is lowered in the well bore and rotated in the performance of its underreaming operation. The body has a central longitudinal passage 13 therethrough merging into diametrically opposed elongate slots 14 opening outwardly of the body. A pair of cutter blades 15 of the drag type are movable within the slots,

2

being mounted upon a hinge pin 16 extending through the body and across its passage 13.

The cutters 15 have an initial downward position substantially completely retracted within the confines of the body 10, and are swingable outwardly in opposite directions to extend beyond the periphery of the body, occupying a generally horizontal position, with their upper sides 15a engaging the upper shoulders 17 of the longitudinal slots 14. A second set of longitudinal slots 18 extend upwardly to one side of and above the stop shoulders 17 at the ends of the main slots to provide passages through which drilling fluid may pass for discharge onto the cutter blades 15, in a manner to be hereinafter described.

The blades are swingable inwardly and outwardly of the body slots 14 in response to upward and downward movement of an operating plunger 19 slidable within the central passage 13 of the main body. This plunger includes a tubular plunger body 20 having a transverse hole through depending legs 21 in its lower end for receiving a pivot pin 22, in which the upper ends 20 of a pair of links 23 are pivotally mounted between the legs. The lower end of each link is pivotally attached to a cutter blade 15 by means of a pin 24. It is to be noted that the links 23 are pivoted to the blades on opposite sides of the hinge pin 16, in order that downward movement of the plunger 19 pivots the blades 15 oppositely in upward and outward directions. Such outward movement may continue, as aforementioned, until the blades occupy horizontal positions in contact with the body shoulders 17.

The upper end of the body passage 13 is enlarged in diameter to form a cylinder 25 slidably receiving the upper piston portion 26 of the plunger, which is also enlarged to a diameter greater than the lower plunger body portion 20. A plurality of piston rings 27, or rubber or similar material, are mounted on the piston for slideable sealing engagement with the wall of the cylinder 25 to prevent leakage in both directions around the piston. A spring 28 encircles the smaller diameter plunger body portion 20, one end engaging the lower end 29 of the cylinder and its other end engaging the piston 26. This spring is under compression and tends to elevate the plunger 19 and retract and maintain the blades 15 in their inward position within the confines of the body 10.

The plunger 19 is movable downwardly and the blades expanded outwardly by the pressure of fluid, like drilling mud, pumped downwardly

through the string of drill pipe 12 and acting upon the piston 26. Since it is desired to discharge the drilling fluid onto the cutters 15 to maintain them free of detritus, the fluid continues downwardly through a central passage 30 in the plunger 19 for discharge in opposite directions through elongate slots 31 in the lower portion of the plunger body and through the upper body slots 18 onto the forward cutting faces of the cutter blades. In view of this discharge of fluid, an orifice or restriction is provided in the plunger passage 30 to enable a back pressure to be built up on the high pressure side of the piston 26 sufficient in value to overcome the compressive force of the spring 28, shift the plunger 19 downwardly, and swing the blades 15 outwardly, through the agency of the pin and link connections 22, 23, 24 between the plunger 19 and blades 15. In prior devices, such restriction was placed in the lower portion of the plunger, the fluid expanding outwardly through such restricted portion at a comparatively high velocity and producing a cutting action on the side body walls of the slots 18 and on the blades 15 themselves, shortening the life of the parts considerably.

In the device under consideration and illustrated in the drawings, the restriction for producing the back pressure on the high pressure side of the piston is placed at the upper portion of the plunger and the fluid expansion and lowering of its velocity takes place within the plunger body itself. Specifically, a restricted orifice means 32 is threaded within the piston 26, the passage 33 at the upper end of the orifice being of such diameter as to insure the building up of sufficient back pressure within the cylinder space 25 at the upper end of the body 10. The orifice has a depending skirt 34, of a much greater internal diameter than the diameter of the orifice passage 33, in which a circulation bean or bushing 35 is placed, preferably of a hard metal, such as tungsten carbide. This bushing is clamped between a shoulder 36 at the upper end of the orifice 32 and a spacer sleeve 37 whose lower end rests upon an internal shoulder 38 in the plunger body 20, whose upper end engages the lower end of the bushing 35, and whose intermediate shoulder 39 engages the lower end of the orifice skirt 34. It is to be noted that the internal diameter of the hard metal bushing or bean 35 is much greater than the diameter of the orifice passage 33 and that the internal diameter of the spacer sleeve 37 is no less than the internal diameter of the hard metal bushing 35. If desired, the inner wall 40 of the spacer sleeve 37 may flare outwardly in a downward direction to simulate a Venturi nozzle.

The passage 30 through the plunger body 20 between the lower end of the spacer sleeve 37 and the longitudinal slots 31 is at least equal in diameter to the internal diameter of the spacer sleeve itself, and the elongate diametrically opposite slots 31 in the plunger body have a cross-sectional area at least as great as the area through the plunger body below the spacer sleeve.

If desired, a circulation screen 41 may extend upwardly from the restricted orifice passage 33, having spaced openings 42 to prevent passage of comparatively large particles suspended in the drilling mud into the orifice, which might plug same. This screen portion, however, need not be employed, especially where relatively clean drilling muds are circulated down through the drill pipe.

The underreamer is lowered through a well casing with the plunger 19 held in an upward direction by the compressed spring 28, which insures the inward retracted position of the blades 15 within the confines of the body 10. When the desired position below the casing shoe (not shown) is reached at which an underreaming operation is to occur, the drill pipe 12 and underreamer are rotated and pressure imposed upon the fluid in the drill pipe. Such fluid acts upon the piston 26 and forces it downwardly against the action of the spring 28 to expand the blades 15 outwardly to their fullest extent. A back pressure is built up by virtue of the restricted orifice 32 in the upper portion of the plunger assembly, fluid passing through the restricted orifice passage 33 and expanding outwardly within the hard metal circulation bushing 35 into its passage. The fluid then flows through the spacer sleeve 37 and the plunger body passage 30 therebelow for exhaustion through the opposed longitudinal slots 31 and body slots 18 onto the cutter blades 15, cleaning the latter of detritus and flushing it in the drilling mud to the top of the well bore.

It is to be noted that the fluid increases considerably in velocity in passing through the restricted passage 33 in the upper orifice, and that upon leaving such passage it expands and assumes a much lower velocity, in view of the much larger area through the hard metal bushing passage 35. Such expansion to a lower pressure is ordinarily associated with fluid cutting of the parts contacted by the hydraulic stream. However, since the eroding or cutting force of the fluid stream is against the hard metal bean 35, very little harm to it results, since it is well able to withstand the erosive forces. The fluid has lost much of its high velocity upon expanding into the circulation bean and then proceeds downwardly through the spacer sleeve 37 and outwardly through the opposed plunger body slots 31, all at a comparatively low velocity. The fluid undergoes no expansion in passing outwardly through the slots 31 and impinging on the sides of the body slots 18 and the cutter blades 15 themselves, and as a consequence, does not erode the side walls of the body slots.

Any erosive wear that might occur takes place within the plunger bean 35 itself and within the spacer sleeve 37. These parts are relatively inexpensive and may be easily replaced. For that matter, the occurrence of any erosive wear in the entire plunger body 19 involves only a comparatively inexpensive part which can be easily replaced.

It is, accordingly, apparent that a plunger device for a hydraulic underreamer has been devised in which most, if not all, of the wear or abrading action attributable to the circulating fluid occurs within the plunger itself, which is a comparatively simple part to manufacture and one which is readily replaceable. The underreamer body itself is not subjected to the velocity action of an expanding fluid stream and its life is prolonged substantially.

While I have shown the preferred form of my invention, it is to be understood that various changes may be made in its construction by those skilled in the art without departing from the spirit of the invention as defined in the appended claims.

Having thus described my invention, what I claim and desire to secure by Letters Patent is:

1. An underreamer, including a body adapted

to be attached to a drill string and having a longitudinally extending slot therein, expandible cutter means carried by said body within said slot, means for expanding said cutter means outwardly comprising a tubular plunger in said body having longitudinally elongate outlet means in alignment with said slot for discharging fluid through said slot directly upon said cutter means, means on the plunger providing a flow restricting orifice in the path of fluid flow through said plunger through which all of the fluid moving through said plunger must pass, said orifice being disposed and spaced a considerable longitudinal distance upstream from said outlet means, said plunger being imperforate between said orifice and outlet means, said plunger having an internal cross-sectional area throughout its length between said orifice and said outlet means substantially greater than the internal cross-sectional area of said orifice but no greater than the total area through said outlet means.

2. An underreamer, including a body adapted to be attached to a drill string and having a longitudinally extending slot therein, a pair of expandible cutters pivotally carried by said body within said slot, means for expanding said cutters in opposite directions outwardly of said body comprising a tubular plunger in said body having opposed longitudinally elongate outlets in alignment with said slot for discharging fluid through said slot directly upon said cutters, means on said plunger providing a flow restricting orifice in the path of fluid flow through said plunger through which all of the fluid moving through said plunger must pass, said orifice being disposed and spaced a considerable longitudinal distance upstream from said outlets, said plunger being imperforate between said orifice and outlets, said plunger having an internal cross-sectional area throughout its length between said orifice and outlets substantially greater than the cross-sectional area of said

5 orifice but no greater than the total area through said outlets.

3. An underreamer, including a body adapted to be attached to a drill string and having a longitudinally extending slot therein, expandible cutter means carried by said body within said slot, means for expanding said cutter means outwardly comprising a tubular plunger in said body having longitudinally elongate outlet means in alignment with said slot for discharging fluid through said slot directly upon said cutter means, means on the plunger providing a flow restricting orifice in the path of fluid flow through said plunger through which all of the fluid moving through said plunger must pass, said orifice being disposed and spaced a considerable longitudinal distance upstream from said outlet means, erosion resisting sleeve means in the plunger adjacent and on the downstream side of said orifice means, said plunger being imperforate between said orifice and outlet means, said plunger and sleeve means having internal cross-sectional areas throughout their lengths between said orifice and said outlet means substantially greater than the internal cross-sectional area of said orifice but no greater than the total area through said outlet means.
